UNITED STATES PATENT OFFICE.

GABRIEL MADLAND AND WILLIAM W. DARROW, OF CHICAGO, ILLINOIS, ASSIGNEES
TO CAMEL COMPANY, OF CHICAGO, ILLINOIS, A CORPORATION OF ILLINOIS.

DOOR OPERATING AND SEALING MECHANISM.

Application filed August 6, 1925. Serial No. 48,458.

The present invention relates to door operating and sealing mechanism.

More particularly the present invention relates to operating and sealing means for sliding doors such as are used on freight cars. The present invention is illustrated and described in connection with certain door operating mechanism described and claimed in the patent to Creer No. 1,544,376, granted June 30, 1925. The present invention covers an improvement over the structure shown in the Creer patent referred to, and has for one of its objects the provision of door operating and sealing mechanism involving the use of a minimum of parts.

A further object is to provide door operating and sealing mechanism which may be readily applied to railroad freight cars as now designed and used.

A further object is to provide door operating and sealing means which combine the advantage of easy closure and easy opening of the car door with the advantage that the plans of car thieves to enter a car without breaking the car seal will be effectually foiled.

A further object is to provide a door operating and sealing means which will effectually meet conditions encountered in service.

Further objects will appear as the description proceeds.

Referring to the drawings—

Figure 1 is a fragmentary view illustrating part of the side of a car and a car door having one embodiment of the present invention applied thereto, certain of the parts being shown in section, said section being taken along the plane indicated by the arrows 1—1 of Figure 5;

Figure 2 is a view similar to Figure 1 but showing the parts in a different relationship relative to one another;

Figure 3 is a sectional view taken along the plane indicated by the arrows 3—3 of Figure 1;

Figure 4 is a sectional view taken along the plane indicated by the arrows 4—4 of Figure 1;

Figure 5 is a sectional view taken along the plane indicated by the arrows 5—5 of Figure 1;

Figure 6 is a view similar to Figures 1 and 2 but showing a modified embodiment of the present invention, certain of the parts being shown in section, which section is

taken along the plane indicated by the arrows 6—6 of Figure 7; and

Figure 7 is a sectional view taken along the plane indicated by the arrows 7—7 of Figure 6.

The numeral 10 indicates the side wall of the car, and the numeral 11 indicates a sliding door. One edge of the doorway for said sliding door 11 is defined by the door jamb indicated in Figure 3 by the numeral 12. Stationarily supported by the door jamb 12 is the bracket 13, which may be secured to said jamb 12 and to the side of the car by any preferred means, bolts 14—14 being illustrated for that purpose. It will be noticed that the bolts 14—14 have semi-round heads, which semi-round heads are presented outwardly of the car. The nuts for said bolts are presented to the inside of the car, for burglar-proofing purposes. Mounted upon the sliding door 11 is the bracket 15, which is also supported by bolts 14—14 having their nuts presented inwardly of the car, for burglar-proofing purposes.

The bracket 13, which is carried by the jamb 12, is provided with the outstanding pin or stud 16, which has an enlarged head 16' and which forms a pivotal support for the catch member 17. The bracket 13 is provided with the lug 18 adapted to engage the under side of the catch member 17 to limit movement of said catch member 17 in a clockwise direction. Said catch member 17 may be provided with the slot 19. When desired, the catch member 17 may be moved into position with the pin 16 occupying that end of slot 19 which is nearer the swinging extremity of the catch member 17. Said catch member 17 may then rest upon the lug 18 out of operative position.

Pivotedly carried by the bracket 13 is the operating lever 20 having the handle portion 21 and the operating portion 22. The operating portion 22 includes the toe 23 adapted to engage within the hooked-over portion 24 of the catch member 17. The operating portion 22 of the lever 20 is also provided with the camming surface 25, which camming surface has a progressively increasing radius about the axis of swing of the lever 20. The stationarily mounted bracket 13 has the abutment portion 26 having an abutting surface. It will be clear without detailed explanation that the counter-clockwise movement of the lever 20, as

the parts are viewed in Figures 1 and 2, will result in a camming action between the operating portion 22 of the lever 20 and the abutment portion 26 of the stationarily mounted bracket 13, resulting in the opening movement of the door 11. When the door 11 is open and it is desired to move said door to closed position, the final stages of the closing movement may be accomplished by engaging the toe portion 23 of the lever 20 within the hooked-over portion 24 of the catch member 17. A clockwise movement of lever 20 will result in the effectual forcing of the door to its closed position. The above described functions are described and claimed in the Creer Patent No. 1,544,376 above referred to.

The present invention contemplates the provision of certain improvements over said Creer patent, whereby the car door may be effectually sealed against surreptitious opening.

It has been common practice to provide a hasp fastener, a hasp fastening strap and locking bolt. One of the tricks to which car thieves have resorted has been to saw through the material providing the bottom part of the slot in the locking bolt in which the car seal is mounted, enabling said thief to open the car door without breaking the seal and, after he has left the car, putting the parts back in the positions in which he found them, the saw cut being quite inconspicuous and very likely to be overlooked by the car inspectors. Among the objects of the present invention is the object of providing a structure which will effectually prevent any such procedure on the part of a car thief.

Slidably mounted upon the pin 16 is the locking bolt 27, which locking bolt is adapted to reciprocate in an aperture 28 provided by the bracket 13. Formed integrally with the lever 20 is the hook member 29 having the hooked-over end portion 30. The lower extremity of the locking bolt 27 is adapted to occupy a position in obstructing relationship with the hooked-over end portion 30 of the hook member 29. That is to say, when the door is in closed position and the lever 20 is moved to the limit of its movement in a clockwise direction, the hooked-over end portion 30 of the hook member 29 will be disposed in such a position that when the locking bolt 27 is in its lower-most position, said locking bolt 27 will effectually prevent the opening movement of the door 11 by reason of its obstructing relationship with said hooked-over end portion 30. The bracket 13 is provided with a portion 31 underlying the lower extremity of the locking bolt 27, though providing an opening 32 for permitting ingress and egress of the hooked-over end portion 30 of the hook member 29 of the lever 20. The lower extremity of the locking bolt 27 is provided with the slot 33,

which is adapted to register with the slot 34 in the bracket 13. Said slots 33 and 34 are adapted to receive the sealing ribbon commonly provided for sealing freight car doors.

Inasmuch as the locking bolt 27 is adapted to have a swinging movement about the pin 16, it is a simple matter to hold locking bolt 27 up out of its operative position, as shown in Figure 2. With the locking bolt 27 in inoperative position, no interference is had with the opening and closing of the car door.

According to the embodiment of the present invention shown in Figures 6 and 7, the hook member 29 has not only a hooked-over end portion 30 but has the hooked-over end portion 35 adapted to cooperate with the downwardly extending lock 36 forming part of the bracket 13. The portions 35 and 36 of the hook member 29 and the bracket 13, respectively, will cause the door to lock automatically when said door is moved to closed position and the lever 20 is moved in a clockwise direction. By reason of this construction the door 11 will be held closed when the car is being shunted about, even though the locking bolt 27 is not disposed in its locking position.

The present invention presents the advantage that the portion 31 of the bracket 13 will protect the lower extremity of the locking bolt 27 against attack by thieves. For this purpose the bracket 13 may be of tool resisting steel. Whether or not the portion 31 of the bracket 13 is of tool resisting steel, it will be a practical impossibility for a thief to saw through said portion 31, due to the proximity of the lever 20. It will therefore be impossible for a thief, when the locking bolt is in operative position, to saw through the lower extremity of the locking bolt 27 to permit the raising of said locking bolt without breaking the seal.

As indicated above, all the nuts are presented to the inside of the car, whereby to burglar-proof the entire arrangement. The construction is simple and sturdy, and may be readily made of forgings, whereby great strength and relatively light weight are had.

Though a preferred embodiment of the present invention has been described in detail, many modifications will occur to those skilled in the art. It is intended to cover all such modifications that fall within the scope of the appended claims.

What is claimed is:

1. In a railway car, in combination, a relatively stationary frame member, a relatively movable door member, means for forcing said door to closed position and for holding said door in closed position, said means including a reciprocable bolt upon one of said members and a lever upon the other of said members, and means upon said frame member constituting an abutment for said

5 bolt, said abutment means and said bolt having apertures adapted to coincide with one another for the reception of a sealing member, said abutment means including a portion underlying said bolt and having protective relationship with said bolt to prevent the sawing of said bolt to remove said sealing member.

10 2. In combination, a relatively stationary frame member, a relatively movable door member, a unitary mounting means upon said frame member, a lever upon said door member, said mounting member having mounted thereon a member for cooperation 15 with said lever for forcing said door to closed position, a reciprocable bolt carried by said mounting means, said bolt being adapted to be moved into abutting relationship with said mounting means and said 20 lever for holding said door in closed position, and an abutment portion having cooperating apertures for the reception of a sealing member, said abutment portion comprising a portion for protecting the extremity of said locking bolt to prevent the disengagement of said locking bolt and said sealing member.

25 3. In a railway car, in combination, a relatively stationary frame member, a relatively movable door member, unitary mounting means upon one of said members and a lever upon the other of said members, means carried by said mounting member for co-

operation with said lever for moving said door to closed position, and a swinging and longitudinally reciprocable bolt for cooperating with said mounting member and said lever for preventing the opening of said door, said mounting member and said bolt being provided with cooperating apertures 40 for the reception of a sealing member, said mounting member being also provided with a portion for protecting the extremity of said bolt against surreptitious attack.

45 4. In a railway car, in combination, a relatively stationary frame member, a relatively movable door member, unitary mounting means upon one of said members and a lever upon the other of said members, means carried by said mounting member for cooperation with said lever for moving said door to closed position, and a longitudinally reciprocable bolt for cooperating with said mounting member and said lever for preventing the opening of said door, said 50 mounting member and said bolt being provided with cooperating apertures for the reception of a sealing member, said mounting member being also provided with a portion for protecting the extremity of said 55 bolt against surreptitious attack.

Signed at Chicago, Illinois, this 27th day of July, 1925.

GABRIEL MADIAND.
WILLIAM W. DARROW.
